UNITED STATES PATENT OFFICE.

CHARLES FREDERICK GAUNT, OF BIRMINGHAM, ENGLAND.

BUTTON FOR UNIFORMS.

1,105,266.

Specification of Letters Patent. Patented July 28, 1914.

Application filed November 20, 1912. Serial No. 732,559.

To all whom it may concern:

Be it known that I, CHARLES FREDERICK GAUNT, of Birmingham, England, temporarily residing in the city of Montreal, Province of Quebec, and Dominion of Canada, have invented certain new and useful Improvements in Buttons for Uniforms; and I do hereby declare that the following is a full, clear, and exact description of the same.

My invention relates particularly to shank buttons of the type, particularly, for use with button-holes for fastening uniforms generally; and it has for its object to apply the principle of filigree work to the exposed fastenings of garments such as the tunics, capes and coats of soldiers, seamen, policemen, janitors, porters and others requiring a durable outer garment bearing distinctive marks or insignia, the purpose being to reduce the amount of baser metal required for the frame or body of the button and, proportionately, the precious metal with which it is plated and the labor and chemicals necessary for cleaning.

The invention may be said briefly to consist of a filigree button having a shank with a plurality of points of connection to spaced portions of the filigree design, another feature being extensions of the connected parts of the shank along the back of the design for reinforcement purposes. More specifically speaking, the shank consists of a plurality of loops or staples with elongated feet extending over the back of the design as just mentioned.

Another feature of the invention consists of a disk slit to accommodate the shank and fitted into the back of the button and bearing an enamel finish to serve as a background for the filigree design.

For full comprehension, however, of my invention reference must be had to the accompanying drawings forming a part of this specification in which similar reference characters indicate the same parts, and wherein:

Figure 1 is a plan view of the obverse side of my improved button for uniforms; Fig. 2 is a similar view of the reverse side;

Fig. 3 is a transverse sectional view taken on line A A Fig. 1, and drawn to a larger scale.

The frame of my improved button for uniforms consists of a rim *b* containing and supporting the design consisting in the present instance of the initials B R T united to the rim and to each other by stems *c* of the same baser metal, the obverse side being plated or enameled as required. The reverse side of the design at its middle thereof has brazed or otherwise rigidly secured to separated points a shank consisting of a spider *d* composed of loops or staples with feet conforming to and extending along the side of the portions of the design requiring reinforcement. I have discovered that the outer portions of the design, radially considered, being braced directly by the rim are stronger than the middle portion, and in order to reinforce this weaker portion have devised a reinforcement adapted to serve also as a means for attaching the button to the garment. This member consists preferably of loops or staples *g* the legs of which are extended in length as at *h* and made to conform to the portions of the design immediately surrounding the center thereof as shown clearly in Figs. 1, 2, and 3. The portions *h* are brazed or otherwise rigidly secured to the reverse side of the filigree design.

The colored disk is indicated at *n* and has slots *o* cut therein to pass over the attachment member, while the rim of the button has a thin circumferential flange *p* adapted to be bent over the periphery of the disk and thus retain it in place. This disk may be enameled any desired color to meet regi-mental or other requirements.

A principal advantage of my improved button for uniforms is that the ground work around the design being all cut away the letters or badge stand out prominently and are more readily distinguished at a distance; and the plurality of loops or staples insures that the button will be kept, when sewed on, with its design right way up.

What I claim is as follows:—

A button consisting of a filigree body and

a shank in the form of a plurality of loops or staples having their legs secured to a plurality of separated portions of the reverse side of the filigree design, and such 5 legs having extensions of the points of connection and conforming to the portions of the design to which they are secured.

In testimony whereof I have signed my

name to this specification in the presence of two witnesses.

10

Montreal November 13, 1912.

CHARLES FREDERICK GAUNT.
